UNITED STATES PATENT OFFICE.

EDWIN W. WEBB, OF CHICAGO, ILLINOIS, ASSIGNOR TO STANDARD CAR TRUCK COMPANY, OF CHICAGO, ILLINOIS, A CORPORATION OF NEW JERSEY.

CAR TRUCK.

Application filed October 31, 1923, Serial No. 671,908. Renewed January 29, 1926.

To all whom it may concern:

Be it known that I, EDWIN W. WEBB, a citizen of the United States, residing at Chicago, in the county of Cook and State 5 of Illinois, have invented certain new and useful Improvements in Car Trucks; and I do hereby declare the following to be a full, clear, and exact description of the invention, such as will enable others skilled in the art 10 to which it appertains to make and use the same.

This invention relates to a car truck construction for railway cars and while the invention is applicable to various types of 15 trucks it is particularly directed to what is known as the arch bar construction of truck or side frame. Such trucks have heretofore been constructed with side frames having a tension member which was extended under 20 the bolster columns, which columns were connected at their bottoms by a base which had a straight or horizontal portion beneath which the tension member passed, said tension member being bent upward at 25 each side of said portion.

It is an object of this invention to provide a structure in which the straight or horizontal portion directly under the column base is terminated, and a curved portion 30 used instead, the stress being kept on a straight line on the tension member of the side frame by having the tension member formed of curved or hammock-shape and contacting and secured to the curved portion 35 on the column base.

It is also an object of the invention to provide a novel means for holding the tension member in position on the column base and securing the same thereto.

It is a further object of the invention to provide means securing the tension member to the column base to which means are also secured the tie bars of the side frame which are connected to the bottoms of the journal 40 boxes.

It is still another object of the invention to provide wear plates between the sides of the bolster end which moves vertically between the columns and the sides of the 45 columns.

It is more specifically an object of the invention to provide such wear plates which have flanges embracing the sides of the column and to also secure said wear plates 50 to the bearing plates which support the end 55 to the bearing plates which support the end

of the bolster so that said wear plates are movable with said bearing plate.

These and other objects and advantages of the invention will be fully set forth in the following description made in connection 60 with the accompanying drawings in which like reference characters refer to the same parts throughout the different views, and in which,

Fig. 1 is a view mostly in side elevation 65 of a portion of a car truck, certain parts thereof being shown in vertical section;

Fig. 2 is a view in vertical section taken substantially on the line 2—2 of Fig. 1;

Fig. 3 is a view in horizontal section 70 through one end of the truck taken substantially on the line 3—3 of Fig. 1; and

Fig. 4 is a plan view of a connecting 75 means between the tension member and bolster column.

Referring to the drawings, particularly Fig. 1, a portion of a car truck is shown in which the wheel is indicated in dotted lines as 1, the compression member of the side frame as 2, the tension member of the side 80 frame as 3, and the bolster columns as 4, said bolster columns being connected at the top by a bar 5 made integral therewith and at the bottom by a column base 6 also preferably made integral therewith. The compression member 2 is connected to the rigid column structure by headed and nutted bolts 7, the bar 5 extending at each side of the said compression member forming a groove in 85 which said member is disposed. The column base 6 is formed with an upper flat portion supporting the channel member 8 which extends between the side frames and which is held in place by having an aperture therein fitting over an upstanding lug 9 on said 90 column base. The lower surface of the column base 6 is formed of convex shape or on a curve centrally disposed relatively to said columns. Each column has lugs 10 at its lower corners which, in the embodiment of the invention illustrated, are shown 95 as projecting downwardly at an angle of approximately 45° and projecting somewhat beyond the lower surface of the column base.

The said lugs 10 are bored to receive headed bolts 11 and said bolts pass through clips or plates 12 which are held thereon and tightened by the nuts on the bolts 11. The tension member 3 is of curved or hammock-shape at its central portion and con- 100 105 110

2

tacts the curved lower surface of the column base. The side portions of the tension member 3 extend tangent to the curve at its central portion and at their upper ends 5 are extended horizontally in contact with the compression member 2, and at which point they are bolted to the journal box in the usual standard way. The column base, preferably, has a lug or pin 15 which enters a corresponding aperture formed in the center part 10 of the tension member 3. The clips or plates 12 have outwardly projecting lugs 13 to which are connected, as by the rivets illustrated, the tie bars 14, which, at their other 15 ends, are connected to the bottoms of the journal boxes in the usual standard way.

The channel member 8 supports the spring 16, illustrated as four in number, on which springs is supported the bearing 20 or cap plate 17. The bearing plate is formed with a plurality of transverse grooves in this upper surface in which are disposed the anti-friction rollers 18 which carry the end of the truck bolster 19, which end is also provided with suitable grooves on its lower surface contacting said rollers. The bearing plate 17 has laterally extending side portions or flanges 20 extending at each side 25 of the bolster columns 4 and there is disposed between said plate and each of said columns a wear plate 21. The wear plate 21 has outwardly extending flanges or is of channel shape so as to embrace the sides 30 of the columns 4 and said plate is constructed for vertical movement. In the embodiment of the invention illustrated, the said plate 21 has inwardly projecting lugs 22 which may conveniently be struck up therefrom and which extend above and below the bearing plate 17, as clearly shown in Fig. 1. The wear plates 21 thus move vertically with the bearing plate 17 and contact the bolster columns 4. Said bolster 19 has 35 stop lugs 19^a on its outer end adapted to engage wear plates 21 to limit endwise movement of said bolster.

In assembling the truck, one of the wearing plates 21 is placed against one column at the lowest point thereon while the other 40 wearing plate is placed against the other column in the highest position with the truck bolsters in place. The roller seat can now be inserted between the columns on an angle 45 of about 45° when the lower wearing plate can be moved into position between the bolster and column, after which the springs are placed under the bearing plates 17 on the channel 8.

By the described construction, a very rigid 60 and rugged column structure is provided to which the tension member is easily secured. The tension member has only the one curved bend at its central portion instead of the usual flat central portion with two bends and the stress is kept centrally disposed on said

tension member by the curved surface on the column base. It will be noted that the tension member 3 is secured to the base 6 by means which do not pierce the tension member but are disposed wholly at the outside thereof. By thus having no fastening means passing through the tension member the same is kept of unbroken cross section and is not weakened. It will also be noted that the rigid and integral structure of 70 the columns, the connecting member 5 at the top thereof and the base 6, form an exceedingly rigid structure of side frame and prevent any lateral movement of the column structure on the tension member. Owing to 75 the convex lower surface of the base 6 and the rigid column structure, the latter cannot move longitudinally along the tension member. There is, therefore, an intimate co-operation between the rigid integral column 80 structure and the curved tension member.

By the provision of the wearing plate 21 embracing the bolster column, a large wearing surface is obtained. The bolster bearing plate is still guided on the bolster column 90 and the increased wearing surface between the bolster and columns will greatly prolong the life of both. The wear does not come directly on the bolster and if the plate 21 becomes greatly worn, a new plate can be 95 substituted therefor with small expense.

From the above description it is seen that applicant has provided a very simple and improved structure of car truck. It will, of course, be understood, that various 100 changes may be made in the form, details and arrangement of the parts without departing from the scope of applicant's invention, which, generally stated, consists in a device capable of carrying out the objects above stated, such as shown and described and set forth in the appended claims.

What is claimed is:

1. A truck structure comprising a side frame having in combination, spaced bolster columns, a truck bolster having its end vertically movable between said columns, a spring cap plate also movable between said columns and vertically movable wear plates disposed between said bolster end and said columns, said wear plates embracing said columns and said cap plate embracing said wear plates, said bolster having stop projections at its outer end adapted to engage said wear plates.

2. A truck structure for railway cars comprising a side frame having spaced columns connected at their lower ends by a base having a centrally disposed convex lower surface, and a tension member extending centrally beneath said surface substantially tangent to and in contact therewith, lugs projecting from said columns at each side of said member substantially at the point of tangency, and means bolted to said lugs

extending beneath said member securing the same to said columns.

3. A truck structure for railway cars comprising a side frame having spaced bolster columns connected at top and bottom, a compression member extending across the top of said columns and bolted thereto, a tension member engaging said compression member at the ends thereof and having a curved hammock-shaped portion extending centrally under and engaging said columns, and removable means secured to each side of said columns spanning said tension member and securing the same and said columns together whereby said tension member is not perforated.

4. A truck structure for railway cars comprising a side frame having a column structure comprising spaced columns, a bar integral with said columns connecting the same at the top, a compression member detachably secured to said bar, a base integral with and connecting said columns having a convex lower surface, a tension member downwardly curved at its central portion extending beneath said base contacting said surface and detachably secured thereto, said columns having lugs at their lower corners projecting at the outer sides of said tension member, and plates spanning said lugs extending beneath and in contact with said tension member bolted to said lugs.

5. A truck structure for railway cars comprising a side frame having spaced bolster columns, a column base connecting the same at the lower ends thereof having a centrally disposed convex lower surface, lugs projecting downwardly from said base beneath the sides of each column, a tension member contacting said surface and disposed between said lugs, and means secured to said lugs securing said tension member to said columns.

6. The structure set forth in claim 5, and tie members secured to said means and adapted to be attached to the bottom of the journal boxes.

7. A truck structure comprising a side frame having in combination, spaced bolster columns, a truck bolster having its end vertically movable between said columns, a spring cap plate also movable between said columns and vertically movable wear plates embraced by said cap plate disposed between said bolster end and said columns.

8. The structure set forth in claim 7, said wear plates having inwardly projecting portions embracing said cap plate.

9. A truck structure comprising a side frame having spaced bolster columns, a truck bolster having its end vertically movable between said columns, a bearing plate supporting said bolster end and wear plates embraced by said bearing plate and embracing said columns vertically movable with

said bearing plate and disposed between said bolster and said columns.

10. A truck structure comprising a side frame having spaced bolster columns, a truck bolster having its end vertically movable between said columns, a bearing plate supporting said bolster end and wear plates vertically movable with said bearing plate disposed between said bolster and said columns and having side flanges embracing said columns, said bearing plate having side extensions embracing said wear plate flanges.

11. The structure set forth in claim 10, said wear plates having lugs extending inwardly therefrom above and below said bearing plate so as to be vertically movable therewith.

12. A truck structure comprising a side frame having in combination, spaced bolster columns, a truck bolster having its end vertically movable between said columns, a spring supported bearing plate having rollers thereon on which said bolster end rests, and separate wear plates vertically movable with said bearing plate and disposed between said bolster end and said columns whereby said wear plates can be replaced when worn without replacement of said bearing plate.

13. A truck structure for railway cars comprising a side frame having spaced bolster columns connected by a base having a curved lower surface, a tension member extended centrally beneath said base in contact with said surface, and fastening means securing said tension member and base together, said fastening means being disposed at each side of and wholly without said tension member.

14. A truck structure for railway cars comprising a side frame having spaced bolster columns, a top cross member and a base member all integrally connected, a compression member secured to said top cross member, said base member having a lower convex surface, a tension member extending centrally beneath said base member in contact therewith and extending upwardly at each side thereof, and fastening means connecting said tension member and base member at each side of and passing wholly outside of said tension member.

15. The structure set forth in claim 12, said wear plates embracing said columns and said bearing plate embracing said wear plates.

16. In a car truck, the combination with a side frame structure, including columns, bolster springs, a bolster supported by said springs and arranged for endwise movement, wear plates disposed between the adjacent faces of said bolster and said columns, said wear plates being arranged to move with said springs, and inter-engaging

abutments on said wear plates and said columns to permit vertical sliding movement and restrain lateral movement of said wear plates.

5 17. In a car truck, the combination with a side frame structure including columns, bolster springs, a bolster arranged for endwise movement with respect to said side frame, means mounted upon and movable vertically with said springs and arranged to support said bolster thereon, said means being provided with inter-locking flanges, and wear devices interposed between the adjacent faces of said columns and said bolster, said wear devices being provided with means arranged to detachably interlock with means on said supporting means.

10 18. A truck structure comprising a side frame having spaced bolster columns, a truck bolster having its end vertically movable between said columns, a roller bearing plate supporting the end of said bolster,

and wear plates detachably interlocked with said bearing plate and movable vertically therewith and respectively disposed between said columns and bolster.

15 19. A car truck having in combination, a side frame comprising spaced bolster columns, a plurality of springs supported in said side frame, a bolster having its end extending between said columns and arranged for endwise movement in respect to said side frame, a member mounted upon and vertically movable with said springs for supporting said bolster, said member being provided with interlocking means, and wear devices interposed between the adjacent faces of said columns and said bolster and being provided with means arranged to detachably interlock with said interlocking means on said supporting member.

In testimony whereof I affix my signature.

EDWIN W. WEBB.
